CLAIM

The ornamental design for a user interface for a display, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a user interface for a display, showing the new, original and ornamental design.

The broken line showing of a computer display, windows, and other elements including the four arrows is included for the purpose of illustrating environment and forms no part of the claimed design.

1 Claim, 1 Drawing Sheet Figure
